UNITED STATES PATENT OFFICE.

ROBERT J. HEWETT, OF WESTFIELD, NEW JERSEY.

CAB SIGNAL SYSTEM.

1,295,896.

Specification of Letters Patent.

Patented Mar. 4, 1919.

Application filed April 17, 1917. Serial No. 162,625.

To all whom it may concern:

Be it known that I, ROBERT J. HEWETT, a citizen of the United States, residing at Westfield, in the county of Union and State 5 of New Jersey, have invented certain new and useful Improvements in Cab Signal Systems, of which the following is a full, clear, and exact description.

This invention relates to railway signal 10 systems and more particularly to signal systems in which the signals are carried by the traveling vehicle.

The primary object of the invention is to provide a normal danger signaling system of 15 this character which is adapted to give either two or three signal indications and which will possess a high factor of safety, that is, one which is normally inactive and cannot be actuated to give a "proceed" signal, except when the vehicle is at predetermined 20 points along the trackway and the control circuits which are normally open, are closed.

The invention will be clear from the detailed description hereinafter to follow, 25 taken in connection with the accompanying drawings, and will furthermore be particularly pointed out in the appended claims.

In the drawings:

Figure 1 shows one embodiment of the 30 signaling system in which two different signal indications are positively given within the vehicle; and

Figs. 2 and 3, when combined, show another embodiment of the invention, providing 35 a signaling system in which three positive signal indications are given within the vehicle.

In Fig. 1, a trackway is shown which is 40 divided into blocks, T^0 , T^{10} , T^{11} , T^{12} , T^{13} , etc., which blocks are connected together by roadside control circuits, which are of a standard type, and will be hereinafter described in connection with the operation of the system. Diagrammatically shown at spaced intervals 45 along the trackway are the vehicle signals and their circuits, the vehicles being indicated in the present illustration as train A, train B and train C. The signals and signal circuits upon each of the vehicles are the same and are controlled by cab relays which have been designated CA, CB, CC. Each relay is connected by a wire 67 to the wheels 68, the other side of the relay being electrically connected by wires 66 and 65 to a rod 50 62, which is slidably mounted for vertical movement within insulated guides 63. The

rod 62 carries at its lower end a contact shoe 61, which is electrically connected thereto and which is adapted to contact with the contact rails D^{15} , H^{16} , D^{17} , H^{18} , etc., which 60 are spaced at determined distances along the trackway at the usual locations of the "distant" and "home" semaphore signals along a trackway. These locations are indicated in the preferred embodiment of the invention by stationary masts or markers which have been indicated 15, 16, 17 and 18, the markers 15 and 17 being "distant" markers and the markers 16 and 18, "home" markers. The upper end of the sliding rod 62 carries 65 a head 64 which is insulated from the contact shoe 61, and controls a circuit controller or spring contact 73. The signals upon the vehicle have been indicated 77 and 80, respectively, and correspond to the "stop" and 70 "clear" signals, which signals may consist of red and green lamps or any other suitable type of visual or audible signals. The signals 77 and 80 are in parallel branches of a circuit which is energized by a battery 71, 80 and includes the spring contact 73, the complete circuit for the signals being hereafter traced in connection with the operation of the device. Both of these signal circuits are therefore normally open, since the spring 85 contact or switch 73 is biased to assume an open position, unless mechanically moved to closed position by the upward movement of the rod 62 when the latter is in engagement with one of the contact rails D^{15} , H^{16} , etc. 90

The three different conditions of the vehicle signal system are shown by the three different vehicles along the trackway and the circuit arrangements will be made clear by tracing the circuits which affect these different conditions. 95

First referring to train B, the signal system upon this vehicle is in its normal or inactive condition, since the contact shoe 61 is not in engagement with one of the contact rails and the circuit to both of the signals 77 and 80 is open at the spring contact 73, as described. 100

The signal system for train C is shown in its "clear" condition with its green lamp 80 105 lighted. The circuits for giving the "clear" signal 80 are closed as follows. Since contact shoe is on home contact rail H^{18} , the rod 62 has been moved upwardly to cause the insulated head 64 to act against the spring 110 contact 73 to close the circuit to the green lamp as follows: from battery 71, wire 72,

spring contact 73, wire 74, front contact 82 of relay CC, wire 81, "clear" signal or green lamp 80, wire 79 and wire 78 back to the battery 71. To close this signal circuit, it is 5 essential that the relay CC be energized from the contact rail H¹⁸, which is accomplished by the current from the battery 55, as follows: from battery 55, wire 54, contact 53 of line relay L¹⁸, wire 52, home contact 10 rail H¹⁸, contact shoe 61, sliding rod 62, wire 65, wire 66, cab relay CC, wire 67 to the axle and wheel 68 of the engine, track rail 59, wire 58, contact 57 of line relay L¹⁸, wire 56, back to the battery 55. The block from 15 the home marker 18 to the next home marker 20 (not shown) is assumed to be unoccupied, since the line relay L¹⁸ is shown to be in its energized position, which closes contacts 53 and 57 forming a part of the circuit just described, which permits the current to pass 20 from the battery 55 to energize the cab relay CC.

Referring now to train A, the presence of the vehicle or train C in the track section T¹² deenergizes the track relay R¹², in the usual manner, and the presence of the train B in the track section T¹¹ deenergizes the track relay R¹¹ and the open condition of the contact 32 of the track relay R¹¹ and 25 also the open condition of the contact 34 of the track relay R¹² prevents the energization of the home line relay L¹⁶ located at the home marker 16. Since this relay L¹⁶ is deenergized, the contacts 53 and 57 will 30 be in their open position and no current will pass from the battery 55 to the contact rail H¹⁶ and the open condition of the contact 24 will prevent current from flowing from battery 26 to the distant line relay L¹⁵, which 35 is located adjacent to the distant marker 15. Since the distant line relay L¹⁵ is deenergized, the contacts 43 and 47 controlled by this relay will be in their open condition, which will prevent the distant contact rail 40 D¹⁵, with which the contact shoe 61 of train A is in engagement from receiving current from the battery 45. Therefore, since contact rail D¹⁵ is deenergized, no current will 45 pass through the circuit of the cab relay CA, which will remain deenergized, and its back contact 75 will remain closed as in the 50 normal or inactive position, as shown by train B. However, since the engagement of the contact shoe 61 with the contact rail 55 D¹⁵, will move the rod 62 upwardly, the spring contact 73 will mechanically close the signal circuit at this point so that the 60 circuit to the red lamp will be closed as follows: from cab battery 71, wire 72, spring contact 73, wire 74, back contact 75, wire 76, red lamp 77, wire 78, back to the cab battery 71. The display of the red light 77 within the vehicle when at a distant marker indicates to the engineman that the block from the 65 home marker 16 to the home marker 18 is

occupied, and since this red signal is displayed at a distant marker the "stop" indication is qualified, and will be interpreted as authorizing the engineman to proceed at "caution" to the home marker 16, prepared 70 to stop on home contact rail H¹⁶ and to wait at this point for a clear signal indication, which can only be given when both trains B and C pass out of the block to permit both the track relays R¹¹ and R¹² to again be 75 energized to close the circuit to the home line relay L¹⁶.

Figs. 2 and 3, when combined, show another embodiment of the invention in which three positive signal indications are adapted to be given in the cab, as for example, by the lighting of red, yellow and green lamps, which correspond to the zero, 45° and 90° positions of a three-position semaphore signal. The red, yellow and green lamps are 80 designated 77, 83 and 80, respectively, all of which lamps are included in parallel circuits with a battery 71 and the spring contact 73. The circuit for the red lamp is similar to the circuit for the red lamp in 85 the first modification, and is as follows: from battery 71 to wire 72, spring contact 73, wire 74, back contact 75 of the cab relay, wire 76, lamp 77, wire 78, back to the battery 71. The circuit for the green lamp 80 90 differs from the one shown in the first modification in that it includes a polarized armature 87 which is controlled by the cab relay, the circuit for this lamp being as follows: from battery 71 to wire 72, spring contact 73, 95 wire 74, front contact 82 of the neutral armature, wire 82' to polar armature 87, polar contact 87^a, wire 81 to the green lamp 80, wires 79 and 78, back to the battery 71. The circuit for the yellow lamp or "caution" 100 signal 83 is also controlled by both the neutral and polar armatures of the cab relay, the circuit for this lamp being as follows: from battery 71, wire 72, spring contact 73, 105 wire 74, front contact 82 of the neutral armature of the cab relay, wire 82', polar armature 87, polar contact 87^b, wire 88 to the yellow lamp or caution signal 83 and wires 79 and 78, back to the battery 71. The cab relays CA, CB, etc., are similar to the 110 modification previously described, connected in circuit with the contact shoe 61 which is adapted to engage with the contact rails D¹⁵, H¹⁶, D¹⁷, H¹⁸, etc.

The control circuits which are of the 115 polarized type, will be rendered clear by tracing the circuits which affect the signals in the vehicle designated trains A, B, C and D, which are spaced along the trackway.

Referring first to train A, the line control 120 circuit for the line relay L¹⁶ at the home marker 16, is as follows: from relay L¹⁶, wire 101, contact 102 of the track relay R¹¹ (which is now in open condition, due to train B upon the trackway), line wire 103, contact 104 of 130

track relay R¹², wire 105, contact 106 of line relay L¹⁸, wire 107, battery 108, wire 109, contact 110 to the common wire of the system back to the line relay L¹⁶.

- 5 The presence of the train B in the track section T¹¹ holds track relay R¹² deenergized and its contact 102 is in open condition as described, which maintains the circuit to the line control relay L¹⁶ open and hence 10 this relay deenergized. The contacts 35 and 43 of the line relay L¹⁶ are therefore open so that no current passes from the battery 39 to the home contact rail H¹⁶. The circuit to the distant line relay L¹⁵ which is 15 in multiple with the home contact rail H¹⁶ by means of wire 96, contact 95 of track relay R¹⁰, wire 94, line relay L¹⁵, wire 99, contact 98 of relay R¹⁰ and wire 97, is therefore also open so that the line relay L¹⁵ is 20 deenergized. The contacts 127 and 135 of the line relay L¹⁵ are therefore in open position, which prevents the current passing from the battery 131 to the distant contact rail D¹⁵. The presence of the train B in the 25 track section T¹¹ therefore leaves the home contact rail H¹⁶, and the distant contact rail D¹⁵ without current. Train A upon the track section T⁹ therefore receives no current from the contact rail D¹⁵ and its cab 30 relay CA remains deenergized, but the upward movement of the sliding rod 62, due to the engagement of the contact shoe 61 with the contact rail, will move the spring contact 73 upward to close the circuit to the 35 red lamp 77, which circuit has been previously traced. The display of a "red" or "stop" signal within the cab or vehicle, is qualified or interpreted in view of the fact that this signal is received when the contact 40 shoe is upon a distant contact rail to authorize the engineman to proceed at "caution" past the distant marker 15 to the home marker 16, where in case the train B still remains in either track section T¹¹ or T¹², the 45 train A will receive a "stop" signal when the contact shoe 61 engages with the home contact rail H¹⁶. This stop signal is given when a train occupies either of the track sections T¹¹ or T¹², which will cause a deenergization 50 of the line relay L¹⁶, as described.

The train B, which is also disclosed in Fig. 2, is in such a position along the track-way that its contact shoe 61 is not in engagement with any of the contact rails along 55 the trackway so that the sliding rod 62 is in its normal inactive position and the spring contact 73 is open. Since each of the cab signal circuits pass through this 60 spring contact 73, all three signal circuits are open and no signal can be given.

Referring now to train C, which has its contact shoe in engagement with the home contact rail H¹⁸, the line control relay L¹⁸, corresponding to this home contact rail, is 65 energized by a line control circuit which is

similar to that described for the line control relay L¹⁶, and is as follows: from line relay L¹⁸, wire 101, contact 102 of track relay R¹³, line wire 103, contact 104 of track relay R¹⁴, wire 105, back contact 113 of line 70 relay L²⁰ (which is deenergized), wire 109, to the negative terminal of battery 108, wire 111, back contact 112, to the common line wire of the system, back to the line control relay L¹⁸. Line relay L²⁰ is deenergized, 75 since the presence of the train D within the track section T¹⁵ which deenergized the track relay R¹⁵, whose contact 102 controls the circuit of the line relay L²⁰. The back contacts 113 and 112 are therefore closed 80 and these contacts serve as pole changers for the battery 108, so that the current delivered to the line relay L¹⁸ passes through it in a reverse direction to the normal direction, which will cause the polar contacts 85 41 and 37 to be thrown to the left (as shown), which will cause a reverse current to be carried from the battery 39 to the home contact rail H¹⁸, the polar contacts 37 and 41 serving as pole changing switches for the 90 battery 39. The cab relay CC, when the contact shoe 61 of the train C is in engagement with the home contact rail H¹⁸, therefore receives a reverse current which passes therethrough and causes its polar contact 95 87 to be thrown to the left (as shown), which will close the circuit to the yellow lamp 83, which is the caution signal, the circuit for the lamp being as follows: from battery 71, wire 72, spring contact 73, wire 100 74, front neutral contact 82, wire 82', polar armature 87, polar contact 87', wire 88 to the yellow lamp 83 and wires 79 and 78, back to the battery 71. The lighting of the yellow lamp 83 indicates to the engineman 105 that the block from the home marker 18 to the home marker 20 is clear, but that the next block is occupied, and the train C will then proceed at "caution" expecting to receive a "stop" or a "clear" signal at the 110 distant contact rail D¹⁹, and also at the home contact rail H²⁰. The "yellow" light 83 therefore gives the usual cautionary or one-block indication.

The "green" light or "clear" signal 80, 115 which is shown in its signal indicating position upon train D, gives the clear or two-block indication. Assuming that there are two clear blocks ahead of the home marker 22, line relay L²² corresponding to this 120 marker will be energized in its normal magnetic condition and its polar contacts 41 and 37 will be thrown to the right and the home contact rail H²² and also the distant contact rail D²¹ will receive a current of normal 125 direction from their respective batteries, the home contact rail H²² receiving current from the battery 39, and the distant contact rail D²¹ from the battery 131. Since the train D is shown with its contact shoe in engagement 130

with the distant contact rail D²¹, and since this distant contact rail receives current of normal direction from the battery 131, the cab relay CD will be energized by a current 5 passing through it in the normal direction, which will cause the polar contact 87 to be thrown to the right, thereby closing the circuit to the green light as follows: from battery 71, wire 72, spring contact 73, wire 74, 10 neutral front contact 82, wire 82', polar armature 87, polar contact 87^a, wire 81, to signal lamp 80, wires 79 and 78 back to the battery 71. The display of the green light 80 will indicate to the engineman that there 15 are two blocks clear in advance of the home marker 22, and as the train proceeds along the trackway, since the condition of the line relay L²² controls the condition of the distant line relay L²¹, the same signal indication will be given when the contact shoe of 20 the train D engages with the home contact rail H²².

It will therefore be seen that in this modification, three different signal indications 25 are given in the cab which are, in all respects, similar to the three positions of a semaphore comprising a part of a roadside signal system, and will have the same factor of safety as a normal danger roadside signal 30 system, since each of the cab circuits is normally open, and hence inactive and can only be closed when the apparatus is in proper condition and the contact shoe is in engagement with one of the contact rails along the 35 trackway, after which condition is fulfilled the red, yellow or green signals indicating "danger," "caution," and "green" may be given, when the line control circuits are intact. This is also true of the modification 40 shown in Fig. 1 with the exception that only "danger" and "proceed" signals are given in that form, and it is not the intention to limit the invention to the particular signaling systems disclosed only by the scope of the 45 claims appended hereto.

I claim:

1. In a railway signal system, a plurality of normally inactive signals carried by the vehicle, a normally inactive circuit controlling each signal, mechanical means carried 50 partially by the vehicle and partially along the trackway for rendering active one of said circuits and the signal controlled thereby, at determined points along the trackway, 55 and electrical means, coöperating with said mechanical means and controlled by traffic conditions, for rendering active the second of said circuits and the signal controlled thereby, at the same determined points along the trackway.

2. In a railway signal system, a plurality of normally inactive signals carried by the vehicle, a normally inactive circuit controlling each signal, mechanical means carried 60 partially by the vehicle and partially along

the trackway for rendering active one of said circuits and the signal controlled thereby, at determined points along the trackway, and electrical means, coöperating with said mechanical means and controlled by 70 traffic conditions, for rendering inactive the first circuit and simultaneously rendering active the second of said circuits and the signal controlled thereby, at the same determined points along the trackway. 75

3. In a railway signal system, a plurality of normally inactive signals carried by the vehicle, a normally open circuit controlling each signal, mechanical means carried partially by the vehicle and partially along the 80 trackway for closing one of said circuits and actuating the signal controlled thereby, at determined points along the trackway, and electrical means, coöperating with said mechanical means and controlled by traffic 85 conditions, for closing the second of said circuits and actuating the signal controlled thereby, at the same determined points along the trackway.

4. In a railway signal system, a plurality 90 of normally inactive signals carried by the vehicle, a normally open circuit controlling each signal, mechanical means carried partially by the vehicle and partially along the trackway for closing one of said circuits 95 and actuating the signal controlled thereby, at determined points along the trackway, and electrical means, coöperating with said mechanical means and controlled by traffic conditions, for opening the first circuit and 100 simultaneously closing the second of said circuits and actuating the signal controlled by the latter, at the same determined points along the trackway.

5. In a railway signal system, a plurality 105 of normally inactive signals carried by a vehicle, a normally inactive circuit for controlling each signal, each of said circuits being open at one point, one of said circuits being normally open at a second point and 110 another of said circuits being normally closed at a second point, and means carried partially by said vehicle and partially along the trackway for closing each of said circuits at said first named point at determined 115 points along the trackway and for closing the normally open second point of one circuit and for opening the normally closed second point of the other circuit at the same determined points along the trackway 120 but in accordance with traffic conditions.

6. In a railway signal system, a normally 125 inactive signal carried by a vehicle, a normally inactive circuit for controlling said signal, said circuit being normally open at at least three points, a mechanical circuit controller controlling one point, a neutral relay controlling another of said points, and a polarized relay controlling the third point, and means carried by said vehicle co- 130

- operating with means along the trackway for closing said circuit at said three points under determined traffic conditions.
7. In a railway signal system, three normally inactive signals carried by a vehicle, a normally open circuit for controlling each of said signals, means on the vehicle for closing each of said circuits at one point, means on said vehicle for opening one of 10 said circuits at a second point and closing the two other circuits at a second point, means for opening one of said last two named circuits at a third point and for closing the other of them at a third point, and means 15 along the trackway controlled by traffic conditions for controlling said means carried by the vehicle.

8. In a railway signal system, three normally inactive signals carried by the vehicle, a normally open circuit for each of 20 said signals, a mechanical switch for closing each of said circuits at one point, a neutral relay switch for opening one of said circuits at a second point and closing each of the other two circuits at a second 25 point, and a polarized relay switch for opening one of said two last named circuits at a third point and for closing the other of them at a third point, and ramp rails and control circuits along the trackway for actuating 30 said switches.

In witness whereof, I subscribe my signature.

ROBERT J. HEWETT.
